UNITED STATES PATENT OFFICE.

CHARLES W. WALTERS, OF OGLETHORPE, GEORGIA.

TICKET-HOLDER.

SPECIFICATION forming part of Letters Patent No. 300,172, dated June 10, 1884.

Application filed March 31, 1884. (No model.)

To all whom it may concern:

Be it known that I, CHARLES W. WALTERS, a citizen of the United States, residing at Oglethorpe, in the county of Macon and State of Georgia, have invented a new and useful 5 Ticket-Holder, of which the following is a specification, reference being had to the accompanying drawings.

My invention relates to ticket-holders designed for use by travelers, whereby the ticket may be displayed at all times, so as to be plainly visible to the conductor or other person, and thus obviate the inconvenience of having to look for the ticket; and it has for 10 its object to provide a device of this character which shall retain the ticket to prevent its dropping from the holder, and one that may be readily attached.

With these ends in view the invention consists in the improved construction and combinations of parts hereinafter fully described, and pointed out in the claim.

In the drawings, Figure 1 is a perspective view of a ticket-holder, showing the ticket 20 therein. Fig. 2 is a transverse section. Fig. 25 3 is an end view, and Fig. 4 is a bottom view.

In the accompanying drawings, in which like letters refer to corresponding parts in the several figures, A represents the casing or 30 holder, which consists of the back B, having secured thereto a pin, C, for its attachment to the clothing of the user.

I am aware that previous to my invention a ticket-case has been provided consisting of 35 an outer casing open at one end and having an opening on its upper side, a drawer fitting in said casing and having a slot in its forward end wall for the passage of a ticket, said drawer being provided with a false bottom, and a spring 40 bearing against the under side of the same. My device differs from this construction, in that it consists simply of a casing having a slot in its end wall and an opening in its upper side, and a plate sliding vertically in said 45 casing, being held in close contact with the under portion of the upper side thereof by means of a flat spring bearing against the under side of said plate, thus obviating the use and needless expense of an inner casing or 50 drawer.

D represents the ends, which are secured to

the back or base B, and having their ends turned inwardly to form guides for the retention of the ticket when inserted between said guides and the back or base B, one of said ends being provided with an opening for the passage of the ticket. Between the guides formed by the inturned sides and ends and the base B is a plate, E, between the under side of which and the base B is secured a spring, 55 F, by which means the said plate is securely held in close contact with said guides, and in this manner prevent the ticket from dropping out or becoming disengaged from the holder.

In the operation of my invention the ticket 60 is inserted between the plate E and the guides of the sides and ends D, and is slid therein, where it is held by means of said spring-pressed plate E. When it is necessary to remove the ticket, the spring-pressed plate is 65 depressed, and at the same movement the ticket withdrawn or slid out.

It will be seen from the above description that by the use of my device it is only necessary to place the ticket in the holder and attach the same to some conspicuous place upon the clothing where it may be readily seen by the conductor, and in this manner the disturbance and annoyance to the passenger while reading, or, as is often the case, while sleeping, is obviated.

It will also be seen that my improvement is simple, may be manufactured and supplied at a slight cost, and that it affords efficient means for the purpose for which it is designed.

Having fully described my invention, what I claim as new, and desire to secure by Letters Patent, is—

The combination, with a casing, A, having an opening in its upper side, and a slot, E, in 90 one of its ends, of a plate located in said casing, a flat spring interposed between said plate and the bottom of the casing, and a catch and pin secured to the back of said casing, substantially as set forth.

In testimony that I claim the foregoing as my own I have hereto affixed my signature in presence of two witnesses.

CHARLES W. WALTERS.
